BLINDSTITCH PRESSER FOOT

Victor J. Sigoda, Great Neck, N.Y., assignor to Man-Sew Corporation, New York, N.Y., a corporation of New York

Filed Sept. 5, 1962, Ser. No. 71,573

Term of patent 14 years

(Cl. D70—2)

FIG. 1 is a front perspective view of a blindstitch presser foot showing my new design. The broken line showing of a fabric folder is for purposes of illustration only.

FIG. 2 is a side elevational view thereof.

FIG. 3 is a top plan view thereof; and

FIG. 4 is a bottom plan view.

I claim:

The ornamental design for a blindstitch presser foot, substantially as shown and described.
